ELECTRON DISCHARGE DEVICE

Johan Lodewijk Hendrik Jonker and Bernardus Octavianus Maria Gall, Eindhoven, Netherlands, assignors to N. V. Philips' Gloeilampenfabrieken, Eindhoven, Netherlands

Application May 27, 1938, Serial No. 210,328
In Germany June 14, 1937

2 Claims. (Cl. 250—27.5)

This invention relates to a multi-grid electron discharge tube having a plurality of control grids and particularly suitable as a so-called mixer tube in superheterodyne circuits. The invention furthermore relates to such a tube and to a circuit in which such a tube can be used.

In the conventional tubes of this type ordinarily between a cathode and an anode a number of grid-shaped electrodes are arranged of which 10 two are employed as control grids, one on which the received signal voltage is impressed and the other on which the local oscillator voltage is impressed. The two control grids are disposed ordinarily directly behind one another which involves 15 the disadvantage that these grids have a high capacity relative to each other.

To reduce this capacity in tubes having a pair of control grids such as for instance the mixer tubes, and octodes, at least one grid serving as a 20 screen grid and having a positive potential is positioned between the control grids. In this case the second control grid usually does not control directly the electrons leaving the cathode but controls a space charge, a so-called virtual cathode, which forms between the positive screen 25 electrode and the second control grid. Though with this arrangement favorable results can generally be obtained, in certain cases such tubes have the disadvantage that due to the space 30 charge which is influenced by the second control grid, a current distribution appears which among other things causes a considerable increase of the rustling noises developed in the tube.

Applicants have found that this disadvantage 35 can be overcome when employing an arrangement and an electron discharge tube in accordance with the present invention. According to our invention a tube having two control grids has positioned between the grids instead of a screen electrode, at a positive potential, screens between 40 parts of the control grids, these screens being connected to a point having zero potential or a fixed negative potential.

Since the control is exerted upon two successive grids so that both control grids influence directly the electrons leaving the cathode, the noise is reduced to a minimum and at the same time the capacity between the two control grids is substantially reduced since the screens are disposed between parts of the grids and are suitably 50 connected to a point having zero potential such as for instance the cathode. These screens are then usually arranged between places of the control grids at which very few electrons appear, for instance in the case of an oval cathode at places

opposite the narrow sides, or in the region of the grid side rods.

In order further to reduce the noise of a discharge tube in accordance with the present invention, in accordance with a specific mode of construction the grid situated at the anode side of the second control grid and which may serve as a screen grid is so designed that the effective parts of this grid are aligned with the effective parts of the second control grid. In other words, the turns of the second control grid and the screen grid are aligned. In order to reduce the screen grid current further it is possible to align also some of all effective parts of control grid 1 with those of the second control and the screen grids. 15

A discharge tube and an arrangement according to the present invention are especially well suited for use in mixer circuits of an intermediate frequency superheterodyne receiving circuit.

In a discharge tube according to the invention and employed as mixer tube the first grid can be used as an input control grid, and the second control grid as an oscillator control grid, or vice versa, whereby the oscillations of the local oscillator may be produced by means of a separate triode. In accordance with a certain mode of construction, according to the present invention, the mixer system and the triode may however also be combined to form a single tube. Such a tube contains in this case an indirectly heated cathode surrounded along a portion of its length by a single grid, and an anode, while there is placed about another portion of the length of the cathode an electrode system as described above and comprising two control grids with interposed screen maintained at zero potential or negative potential, a screen grid and an anode, whereby in addition an absorption or suppressor grid may be arranged between the screen grid and the anode. 30

The novel features which we believe to be characteristic of our invention are set forth with particularity in the appended claims, but the invention itself will best be understood by reference to the following description taken in connection with the accompanying drawing in which Figure 1 is a transverse section of an electron discharge tube made according to our invention, and Figure 2 is a circuit diagram embodying a tube made according to our invention. 40

In Figure 1, the electron discharge device is provided with an indirectly heated cathode and a number of grid-shaped electrodes 2, 3, 4 and 5 surrounding and coaxial with said cathode and which are used respectively in a discharge tube, and an arrangement according to the present 50

invention, as first control grid, second control grid, screen grid and absorption or suppressor grid. Small screen plates 6, which may be of sheet metal, are arranged between the grids 2 and 3 and at places, i. e. between parts at which but few electrons appear, in comparison with the other parts of the grids. The various grids are fastened to supporting rods 7 which all lie in the same plane to provide a field distribution as favorable as possible. Finally, an anode 8 is placed about the said grids. The electrode assembly is placed within an evacuated envelope 8'.

Figure 2 shows a circuit in accordance with the present invention. In this circuit two tubes 9 and 10 are shown of which the first one is employed as triode oscillator, containing a cathode 11, a grid 12 and an anode 13, while the second tube represents a mixer tube in accordance with the invention, containing a cathode 1, two control grids 2 and 3, a screen grid 4, an absorption grid 5 connected to the cathode, then an anode 8, and two small screen plates 6 likewise connected to the cathode. In the drawing there is shown furthermore an input circuit 21, an output circuit 22, and an oscillatory circuit 23 whereby the oscillations produced in the tube 9 are impressed upon the grid 16 of the tube 10 to provide a voltage of intermediate frequency in output 22.

While we have indicated the preferred embodiments of our invention of which we are now aware and have also indicated only one specific application for which our invention may be employed, it will be apparent that our invention is by no means limited to the exact forms illustrated or the use indicated, but that many variations may be made

in the particular structure used and the purpose for which it is employed without departing from the scope of our invention as set forth in the appended claims.

What we claim as new is:

1. An electron discharge device having a straight thermionic cathode for supplying electrons, and an anode surrounding said straight thermionic cathode for receiving said electrons, a pair of control grids surrounding and coaxial with said cathode and anode, each of said grids being provided with a pair of oppositely disposed side rods, said side rods lying in a common plane, and a pair of shielding members positioned between the control grids and lying adjacent said side rods and providing openings on opposite sides of said cathode through which electrons from said cathode may travel to said anode.

2. An electron discharge device having a straight thermionic cathode and an anode surrounding said straight thermionic cathode, a pair of control grids surrounding and coaxial with said cathode and anode, and a screen grid surrounding said control grids, each of said grids being provided with a pair of side rods, said side rods lying in a common plane, and a pair of V-shaped shielding members positioned between the control grids and lying adjacent said side rods and providing openings on opposite sides of said cathode through which electrons from said cathode may travel to said anode, said shields connected to cathode.
